COMBINED WELT SEAM PRESSER FOOT

John Lang, Brooklyn, N. Y.

Application September 19, 1946, Serial No. 698,041

2 Claims. (Cl. 112—235)

1

This invention relates to improvements in presser feet for sewing machines and more particularly to those which are used when sewing a strip of welting cord onto slip covers, cushions and articles of upholstery to provide welt seams therein.

This invention is an improvement on my welt seam presser foot, Patent No. 2,211,333, dated August 13, 1940.

An object of this invention is to provide a presser foot having welt seam cord guiding means adapted for operating on welt seams having various sizes of circular cords therein.

Another object of this invention is to provide a supporting means for a circular welt seam gauge whereby the gauge may be raised a considerable distance for operating on welt seams having cords of large diameter.

Another object of this invention is to provide a welt seam gauge which is adjustable both vertically and sideways to engage cords of different diameters.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of the welt seam presser foot.

Figure 2 is a side elevation of the presser foot shown in Figure 1.

Figure 3 is a top plan view of the presser foot removed from the presser foot bar.

Figure 4 is a top plan view of a modified welt seam presser foot.

Figure 5 is a front elevation of the modified presser foot shown in Figure 4.

Figure 6 is a bottom view of the presser foot shown in Figures 1, 2 and 3.

In the illustrated embodiment of the invention, the numeral 10 indicates a combined welt seam presser foot having a shank 11 which is suitably adapted at its upper end to fit the lower end of a presser foot bar 12. The presser foot 10 may be secured to the bar 12 by a screw 13 threaded into the bar.

The presser foot shank 11 has a rectangular through opening 14 positioned transversely of the line of stitching. An arm 15 is slidably mounted in the opening 14 and is secured to the shank 11

2

by a screw 16. The arm 15 has a downward and forward extension 17. The extension 17 has a threaded aperture 18 and a vertical guideway 19 at its free end.

5 A gauge 20 having a centrally positioned aperture 21 is mounted on a screw 22 threaded in the aperture 18. The aperture 21 in the gauge 20 terminates in line with the needle aperture 25 in the presser foot 10.

The gauge 20 comprises two fingers 26 which are positioned horizontally and overlap the front portion of the presser foot 10.

10 The gauge 20 may be adjusted vertically in the guideway 19. The gauge may also be adjusted horizontally by moving the arm 15 in the opening 14. The lower portion of the gauge 20 in transverse contact with the work has an arcuate contour 27.

These adjustments make it possible to move 15 the arcuate surface 27 to and from the needle and thereby operate on welt seams having various sizes of cords therein with a single gauge and with precision.

15 In my prior patent, No. 2,211,333, I have disclosed a welt seam presser foot wherein a roller gauge is rotatably mounted on an arm, and which produced point contact with the material worked upon. I have found that it is necessary to have

20 an elongated or linear contact of the gauge with the work. Also to terminate the guide bars on the foot and on the gauge past the needle to a small extent to facilitate operations when turning corners on a cushion, etc., worked upon.

25 As shown in Figure 6, the presser-foot 10 has an elongated linear guide bar 30 which terminates past the needle aperture 25. The gauge 20 also has an elongated linear bar 31 which terminates slightly past the needle aperture 25. The presser foot has a feed-dog contact bar 32.

30 Figures 4 and 5 show a modified welt seam presser foot 35 similar to the presser foot 10. The presser foot 35 comprises a rectangular sideways movable member 36 which fits into a rectangular cut-out 37 at the right-hand side of the front end of the presser-foot.

35 The right hand member 36 is supported on the presser foot 35 by a leaf spring 38 and screws 39. A screw 40 passes freely through the member 36 and is threaded into the foot portion of the presser foot 35. By adjusting the screw 40, the member 36 may be moved to and from the foot portion of the presser foot 35.

40 The lower portion of the member 36 in transverse contact with the work has an arcuate contour 41 similar to the contour 27 on the gauge

20. The contour 27' on the gauge 20' on the presser foot 35 also has an arcuate contour.

It is to be noted that the presser foot 35 may be used for making right hand or left hand welt seams and that the elements numbered 16', 17', and 25' are duplicates of similarly numbered elements shown with the presser foot 10. The member 36 has an elongated linear guide bar 41.

It is also to be noted that the presser foot 10 has a substantially semi-circular recess 42 which may be used when making right-hand welt seams having one particular size cord. The presser foot 35 provides an adjustable right-hand presser foot whereby welt seam having different size cords may be worked.

In accordance with the patent statutes I have described and illustrated the preferred embodiments of my invention, but it will be understood that various changes and modifications can be made therein without departing from the spirit of the invention as defined by the appended claims.

I claim:

1. In a welt seam presser foot for sewing machines having a needle, comprising a shank having a downwardly and forwardly extending arm, said arm being horizontally slidably mounted on said shank, a welt seam gauge having a vertical aperture formed therein, threaded means secured to said shank passing through said aperture and permitting vertical adjustment of said gauge, the lower portion of said gauge in transverse contact with the material worked upon having an arcuate contour, said gauge having horizontal fingers in overlapping relation with the front portion of said presser foot and being movable to move said arcuate surface to and from said needle to hold the

stitching of a finished welt seam in alignment with said needle, and said threaded means permitting adjustment of said gauge to permit said foot to operate on welt seams having various sized cords therein.

2. In a welt seam presser foot having an aperture for a sewing machine needle, a shank having a rectangular through opening, an arm slidably mounted in said opening, said arm being positioned horizontally and crosswise of the line of stitching, said arm having a downward and forward extension, said extension having an upright guideway at the free end thereof, a welt seam gauge having a vertical aperture formed therein, threaded means secured to said shank passing through said aperture and permitting vertical adjustment of said gauge, said gauge having a horizontally positioned slot in alignment with said needle aperture, the portion of said gauge in transverse contact with the material worked upon having an arcuate contour and being designed to hold the stitching of a finished welt seam in alignment with said needle, and said threaded means permitting adjustment of said gauge to permit said foot to operate on welt seams having various sized cords therein, said foot and said gauge having guide bars terminating slightly past said needle to facilitate turning of corners of articles having welt seams.

JOHN LANG.
